CAN PERFORATOR AND SPOUT FORMER
Edward P. Hansen, 2311 W. Capitol Drive, and William H. Volkman, 5526 W. Hopkins St., both of Milwaukee, Wis.Filed Dec. 2, 1958, Ser. No. 777,755
1 Claim. (Cl. 30—6.3)

This invention relates primarily to can perforators of the type particularly adapted for perforating a metal container and simultaneously forming a pour lip thereon whereby liquid within the container can be readily drained.

A general object of the invention is to provide an improved can perforator.

Another object of the invention is to provide an improved can perforator particularly adaptable to the opening of cans having a flat top surface such as are found in metal condensed milk containers.

Another object of the invention is to provide an improved can perforator whereby the piercing member is designed to perforate a can top and bend the resulting metal tongue in a manner to flatten the same against the interior wall of the can and to deform the rim of the can to create a pour lip.

According to this invention, an improved can perforator is provided which is particularly adaptable for perforating the top of flat faced cans and provide a pair of pierced openings therein; one of said openings being sufficiently large to permit ready pouring of liquid from the can, and the other opening serving to provide a vent in the can. The can perforator is comprised of two main members which are hingedly secured together to provide a unitary operating mechanism. The lower member is provided with a hook to engage the sidewall of the can directly beneath the top rim thereof. The other or upper member is provided with a pour opening spear and a vent opening spear. A slight downward pressure on the upper member will serve to first bring the pour opening spear into engagement with the top surface of the can and effectively pierce the metal. Continued pressure on the upper member will serve to fold the metal from the pour opening downwardly and rearwardly until such metal meets with the side wall of the can. The spear is shaped to deform the peripheral rim of the can in a manner to create a pour lip thereon. Concomitantly the vent opening spear will have engaged the can top surface diametrically opposite the pour lip opening to provide a smaller vent opening in the can top. The can perforator offers considerable utility to persons who are required to open condensed milk cans and the like. The can perforator can also be used to open cans having an upstanding edge such as beverage cans; in this case, however, the upstanding can ridge or rim is sufficiently strong to partially withstand deformation and, consequently, a pouring lip of reduced size is formed on the rim of the can. The upper member of the can perforator is shaped to provide a bottle cap removal means, while the lower member is swedged to provide a pry lever useful in opening the conventional jam and paint type of container.

The foregoing and other objects of the invention will become more apparent to one who has read the following detailed description and has studied the accompanying drawings, in which:

FIGURE 1 is a perspective view of a can perforator operably disposed on top of a can;

FIGURE 2 is a side view of the can perforator disposed in a closed position on top of a can and showing the

2

perforated metal folded rearwardly against the side wall of the can;

FIGURE 3 is a plan view of a container showing the perforated holes therein as well as the formed pour spout;

FIGURE 4 is a perspective view of the can perforator in a partially closed position in order to show the relationship of the vent and the pour opening spears in the upper member with corresponding openings in the lower member;

FIGURE 5 is a bottom view of the upper member showing the details of the various projecting parts thereof;

FIGURE 6 is a bottom view of the lower member showing the can engaging rim means and the can pry edge thereon;

FIGURE 7 is an elevation of a portion of the device with the bottle cap remover positioned to effect removal of a conventional cap from a bottle; and

FIGURE 8 is also an elevational view of the bottle cap remover disposed on the cover of a jar whereon the cover was pressure mounted.

Can perforators are in a class by themselves among the miscellany of household devices presently available in the modern kitchen. While many different perforators have been developed, most are virtually useless since the average housewife is unable to use them with ease and assurance of success. As a consequence, many housewives resort to the age old technique of applying endwise pressure on an ice pick or knife to force the point thereof through the cover of a container. Resorting to the use of such means has often resulted in physical injuries or mental anguish to the user.

In order to overcome the hazards and uncertainties of using the existing devices allegedly designed for perforating food and liquid containers, a new concept of a combined can perforator, cover and bottle cap opener is hereinafter described.

Referring to the drawings, and more specifically to FIGURE 1 thereof, the can perforator device 10 is shown operatively positioned on the flat top face 11 of a sealed can or container 12. The tool device 10 is comprised of two main members, a lower member 13 and an upper member 14. Initially, the lower member 13 is manually disposed on the top of the container or receptacle 12. A crosswise movement of the device 10 will serve to bring a downwardly projecting and inwardly curved flange hook 15 into engagement with the underside of a peripheral edge or bead 16 of the can 12; at this point further movement of the member 13 is impossible.

As viewed in FIGURE 1, the left end of the member 13 is formed to provide a hinge section 17 designed to fit between a pair of hinge lobes 18 integrally formed on the upper member 14. A hinge pin 19 extending through the hinge section 17 and lobes 18 serves to join the members 13 and 14 together into an operable unit. The clearance between the hinge components is sufficient to permit free movement therebetween with a minimum of manual effort.

The upper member 14 is shaped similar to the lower member 13 excepting that the member 14 is provided with depending longitudinal side edges 20 and 21. These integrally formed edges serve to materially stiffen the member and strengthen the same against laterally applied pressures.

A pour opening spear 22 and a vent opening spear 23 are integrally formed and depending from the bottom face

24 of the member 14, as best viewed in FIGURES 2 and 5. The spear 23 is crowned to impart stability thereto and to serve to enlarge the resulting hole in the can 12. A punched opening 25 in the lower member 13 permits a ready passage for the spear 23 when the can perforator device is manipulated to effect perforation of a container. A punched opening 26 in the member 13 provides corresponding passage for the pour opening spear 22, as shown in FIGURES 1, 4 and 6.

The spear 22 is accurately shaped to pierce the top face 11 of a can 12 and fold the resulting fragment of metal constituting a triangular tongue 27 backwardly against the side wall of the can and effect a distortion of the sidewall to create a pour trough 28. FIGURE 3 is a top view of a can or container 12 after the openings have been cut therein with the numeral 29 indicating the pour opening through which the contents of the can may be poured and the numeral 30 indicating the vent opening. The latter is just large enough to adequately vent the container while the former is sufficiently large to permit the flow of a sizable stream of liquid from the container. As best shown in FIGURES 1, 2 and 5, rib 31 and 31a pressed into a portion of the center section of the member 14 and the spear 22, respectively, functions to make the spear sufficiently strong to withstand the pressures exerted during the perforating operation. After the fragment of metal 27 has been cut, the backside of the spear rib 31a sustains pressure thereon until the triangular tab 27 has been completely folded against the sidewall of the container. Likewise the pour spear 22 is curved as shown in FIGURE 2 to sustain pressure on the triangular tongue 27 during its downward and sidewise travel until it has been completely deformed to meet the curved sidewall of the container 12. The continued force imparted by the rib 31a then serves to deform a portion of the sidewall of the container outwardly until a pronounced pour trough 28 is created. As shown in FIGURE 6, a notch 32 is provided in the flange 15 wherein the rib 31a can fit and crowd the sidewall metal in forming the pour trough 28.

From the foregoing description of the structural details of the can perforator device 10, it should be evident that a very useful household tool has been invented. When the lower member 13 is in place on the top of a can 12, the user of the device need only apply a nominal downward pressure on the extending end of the member 14 to bring the spear 22 into engagement with the top of the can. Continued pressure will effect penetration of the metal, folding, trough formation, and finally vent opening piercing. Any person can manipulate the device to effect a uniform perforation of the can top at two diametrically opposed points with a minimum of effort and time. With this device literally dozens of cans could be perforated in a matter of minutes. Release of the device is accomplished by merely reversing the procedure, namely, raising the upper member 14 until the spears 22 and 23 clear the can top and, thereafter, moving the perforator assembly longitudinally until the flange hook 15 is parted from the edge or bead 16 of the container.

In order to provide the greatest utility, the device 10 includes two additional features which insure multiple uses therefor. The outer end of the member 14 includes an integrally formed bottle cap remover 33 while the outer end of the member 13 includes an integrally shaped pry edge 34 which can be used to remove covers of the type found on paint and syrup containers. The pry edge 34 is sufficiently wide to permit good retention with the container cover regardless of the diametrical size thereof. When used for this purpose, the lower member 13 is grasped independently of the member 14 so that the member can be readily manipulated into position against the container cover. The member is stiffened by the use of stamped ribs 35 and 36 which converge at a point directly behind the pry edge 34. Thus, a considerable lateral pressure can be applied manually to the member 13

for this purpose without fear of bending or twisting the metal adjacent the edge 34. The same edge can be used as screw driver and for other related purposes.

Use of the bottle cap remover 33 for removing a well-known crimped bottle cap 37 from a glass beverage bottle 38 is depicted in FIGURE 7. The removal of the cap 37 is effected by clasping the folded device 10 firmly in a manner to bring an extending hook 39 of the cap remover 33 into engagement with the underside of the cap and with the members 13 and 14 extending across the top of the cap. A slight downward pressure on the extending end of the member 14 will lift the cap from the bottle. The width of the cap remover hook 39 is sufficient to support the underside of the cap 37 over a considerable distance whereby the usual bending and distortion of the cap is eliminated; thus the cap can be readily reused.

Likewise, the use of the bottle cap remover 33 for the purpose of removing the pressure sealed type of jar cover 40 from a jar 41 is shown in FIGURE 8. Such jars are currently used for preserving foods, including fruits, vegetables, jellies and the like. During processing this type of jar is closed through the application of pressure on the cap to force the seal thereof into full engagement with the top lip of the jar. Thus, for purposes of cover removal, the remover 33 is likewise hooked under the cover 40 with the member 14 extending crosswise of the top face of the cover. Manual pressure upwardly on the end of the member 14 in a semi-circular path will bring the shoulder of the extending hook 39 against a shoulder 42 adjacent the top of the jar. This movement serves to raise the hook 39 upwardly against the cover and force the same away from the jar top and permit air to enter the jar. It should be noted that the width of the hook 39 precludes all damage to the cover during removal. Therefore, the cover can be reused repeatedly to reseal the jar without fear that leakage may occur with the usual attendant contamination.

Thus, it should be apparent that the device 10 not only provides an improved means for simultaneously punching two apertures in the top of cans or containers, namely a formed pour opening and a vent opening, but also provides a bottle cap opening means and a container cover pry means. All are included in a single unitary device which is compact and of sufficient strength to withstand the rugged use generally imparted to a household tool of this type.

Anyone who has ever labored in the culinary arts is well aware of the problem of opening containers whether it be by penetration or cover removal and of the prime need for a universal tool of the type described herein to open the various types of containers presently utilized for the containment of foods, paints, and other items of a similar nature.

Although but one embodiment of the invention has been shown and described, it should be apparent to one skilled in the art to which this invention relates that various modifications of the invention are possible without departing from the spirit and scope of the invention as defined in the subjoined claim.

The principles of the invention having now been fully explained in connection with the foregoing description of the embodying structure and as shown in the drawings, we hereby claim as our invention:

A can perforator device operative to effectively perforate and form a pour spout in a container and comprising a lower member disposed to engage the end face of a container, a projecting hook depending from said lower member and having a curved lip edge serving to engage the peripheral sidewall of a container, a forming notch centrally disposed in said curving lip edge, an upper member hingedly secured to said lower member substantially above said hook, a pour spear integrally formed and depending from said upper member, an opening in said lower member to permit free passage of said spear

therethrough, and a crowned rib on said pour spear operatively disposed to be moved adjacent to and facing the forming notch in said hook, the spear being operative to engage and cut a triangular tongue from the top of a container and thereafter form the tongue and adjacent sidewall between said spear rib and said forming notch in said hook whereby a uniformly shaped pour spout is created.
